UNITED STATES PATENT OFFICE

JULIUS A. SCHWEIG, OF ST. LOUIS, MISSOURI

ELEVATOR DOOR

Application filed May 3, 1928. Serial No. 274,690.

This invention relates to elevator doors of the truckable, counterbalanced type wherein the downwardly opening door section when fully opened is supported by suitable brackets with its top surface substantially flush with the door sill and filling the space between said sill and the elevator car so as to support trucks passing thereover.

The principal object of the present invention is to provide the door section with brackets adapted to rest on the door sill in the fully opened position of the door section, whereby loads upon said section are transmitted to said door sill. Another object is to enable the brackets to be adjusted with relation to the door section to bring the upper edge of the door flush with the door sill. Another object is to stiffen and strengthen the upper corners of the door section by means 20 of gusset plates which constitute supports for said brackets and have the door arms formed integral therewith. Other objects are simplicity of construction and economy of design.

25 The invention consists in the elevator door construction and in the combinations and arrangements of parts hereinafter described and claimed.

In the accompanying drawings, which 30 form part of this specification and wherein like symbols refer to like parts wherever they occur;

Fig. 1 is a fragmentary side elevation looking at the shaft side of an elevator door construction embodying my invention;

Fig. 2 is an enlarged horizontal section through one side of the elevator door construction on the line 2—2 in Fig. 1;

Fig. 3 is a fragmentary side elevation looking toward the shaft side of the upper corner portion of the lower door section and the portion of the elevator shaft located adjacent thereto;

Fig. 4 is a vertical section through the upper portion of the lower door section on the line 4—4 in Fig. 3; and

Fig. 5 is a similar section on the line 5—5 in Fig. 3.

Referring to the accompanying drawings, 50 my invention is shown in connection with a

vertical sliding freight elevator door of the truckable, counterbalanced type comprising upper and lower door sections 1 and 2 respectively, for closing the door opening in an elevator shaft. As shown in the drawing, the upper and lower sliding door sections are provided along each vertical side edge with an angle 3 slidably arranged between angle bar guides 4 that are rigidly secured to each other and to the adjacent jamb member 5 of the door opening. The upper and lower door sections are counterbalanced by means of chains 6 suitably connected to the lower corners of the upper door section. Said chains extend upwardly around pulleys (not shown) and thence downwardly in the direction of the lower door section where they are suitably connected to the upper ends of upright chain rods 7 whose lower ends are secured to the outer ends of door arms 8 that project horizontally from said lower door section. The construction of elevator doors thus far described is well known and it is considered unnecessary to illustrate it in detail.

The lower door section 2 comprises a metal edge frame made up of angle iron side frame members 9 and a heavy angle iron top frame member 10, which will be hereinafter referred to as a trucking bar. The door section 2 is provided with metal covered wooden panels 11 that are bolted or otherwise rigidly secured to the angle iron edge frames thereof. As shown in the drawings, each side angle 9 of the door section 2 terminates short of the trucking bar 10 whose top flange extends continuously from side to side of said door section and whose depending side flange terminates short of each side thereof. At each upper corner of the lower door section 2 the adjacent ends of the trucking bar 10 and side angle 9 are rigidly connected together by means of a gusset member in the form of a flanged casting 12 seated in the angles of the trucking bar and side angle. As shown in the drawings, the gusset member 12 is riveted or otherwise rigidly secured flatwise to one flange of the side angle of the lower door section and is also riveted or otherwise rigidly secured to the depending flange of the trucking bar and to the underside of the

100

top flange of said bar. As shown in the drawings, the door arm 8 is made integral with the gusset member and projects horizontally therefrom at the upper corner thereof. The 5 upper corner of the metal clad wooden panel 11 for the lower door section is cut away to accommodate the gusset plate, which is provided along the outer face of the said section with a flange 13 which extends from the 10 lower edge of the depending flange of the trucking bar to the inner edge of the flange of the side frame angle located in the plane of said trucking bar frame.

The brackets or hangers, which serve to 15 suspend the lower door section 2 from the sill 14 of the door opening in the opened position of said section, are shown in the form of angle-shaped members 15 that are arranged with one flange down and disposed 20 opposite the outer face of the door and with the other flange up and projecting outwardly from the door so as to overlap the door sill. As shown in the drawings, one of the supporting brackets 15 is located at each upper 25 corner of the door and is secured to the combined gusset plate and door arm 12 by means of bolts 16 which extend through holes in the depending flange of said brackets and through elongated slots 17 provided therefor 30 in said gusset plate and are provided with nuts 18 adapted to bear against the inner face of said gusset plate. The slots 17 are disposed vertically whereby said support or bracket member may be adjusted vertically on the 35 door to raise or lower the sill engaging flange thereof. The outer face of each gusset plate 12 is provided opposite the depending vertical flange of the supporting bracket 15 cooperating therewith with a series of vertical- 40 ly spaced horizontally extending teeth 19 adapted to cooperate with a similar series of teeth 20 formed on the inner face of said flange of said supporting bracket. By this arrangement, the teeth on the supporting 45 bracket from a series of supports for the teeth on the gusset plate; and the two series of teeth are firmly held in engagement with each other by means of clamping bolts 16. When it is desired to adjust the supporting 50 brackets on the door section, the bolts are loosened to permit the teeth on the supporting bracket to become disengaged from the teeth on the gusset plate, whereby the supporting bracket may be adjusted vertically on the 55 door as far as the elongated slots 17 will permit.

With the arrangement described, the gusset plates 12 at the upper corners of the lower door section serve to greatly increase the 60 strength and rigidity of said section thereof; and they also have the door arms 8 formed integral therewith, thereby dispensing with the use of separate door arms and eliminating the cost of attaching such arms to the 65 door section. The gusset plates also consti-

tute rigid supports for the supporting brackets, which may be quickly and easily adjusted on said gusset plates to raise or lower the sill engaging flanges thereof and thereby bring the upper edge of the trucking bar into alignment with the door sill when the door 70 section is fully opened.

Obviously, the hereinbefore described door construction admits of considerable modification without departing from the invention; therefore, I do not wish to be limited to the 75 precise construction shown and described.

What I claim is:

1. A truckable counterbalanced elevator door comprising a downwardly movable door section having top and side frame members, a separate gusset member directly connecting the adjacent ends of the top and side frame members at each upper corner of said door section and having a door arm formed integral therewith and a supporting bracket adjustably secured to each of said gusset members and adapted to engage the sill of the 80 door opening.

2. A truckable counterbalanced door comprising a downwardly movable door section having a trucking bar at its upper edge and metal frame members at its side edges, a gusset plate connecting adjacent ends of said trucking bar and said side frame members at 90 each upper corner of said door section, a supporting bracket secured to each of said gusset plates and having an outstanding flange adapted to engage the sill of the door opening, means for adjusting said bracket vertically on said gusset plate, and means for rigidly securing said supporting bracket to said gusset plate in any desired position of adjustment.

3. A truckable counterbalanced door comprising a downwardly movable door section having a trucking bar at its upper edge and metal frame members at its side edges, a gusset plate connecting adjacent ends of said trucking bar and said side frame members at each upper corner of said door section, a supporting bracket secured to each of said gusset plates and having an outstanding flange adapted to engage the sill of the door opening, means for adjusting said bracket vertically on said gusset plate, and means for rigidly securing said supporting bracket to said gusset plate in any desired position of adjustment, said gusset plates having door arms projecting horizontally therefrom and 105 formed integral therewith.

4. A truckable counterbalanced door comprising a downwardly movable door section, supporting brackets secured to the outer face of said door section having outstanding flanges adapted to engage the sill of the door opening, and means for adjusting said brackets vertically relative to said door section.

5. A truckable counterbalanced door comprising a downwardly movable door section, 120

supporting brackets secured to the outer face of said door section having outstanding flanges adapted to engage the sill of the door opening, means for adjusting said brackets vertically relative to said door section, and means for rigidly securing said supporting brackets to said door section in any desired position of adjustment.

6. A truckable counterbalanced door comprising a downwardly movable door section having a trucking bar at its upper edge and metal frame members at its side edges, a gusset plate connecting adjacent ends of said trucking bar and said side frame members at each upper corner of said door section, supporting brackets secured to the outer face of said door section having outstanding flanges adapted to engage the sill of the door opening, means for adjusting said brackets vertically relative to said door section, and means for rigidly securing said supporting bracket to said door section in any desired position of adjustment, said gusset plates having door arms projecting horizontally therefrom and formed integral therewith.

7. A truckable counterbalanced door comprising a downwardly movable door section having a trucking bar at its upper edge and metal frame members at its side edges, a gusset plate connecting adjacent ends of said trucking bar and said side frame members at each upper corner of said door section, a supporting bracket mounted on each of said gusset plates and having an outstanding flange adapted to engage the sill of the door opening, cooperating vertically spaced horizontally extending teeth on the opposing faces of said gusset plate and said supporting bracket, whereby said bracket may be adjusted vertically on said gusset plate, and means for rigidly securing said supporting bracket to said gusset plate in any desired position of adjustment.

8. A truckable counterbalanced elevator door comprising a vertically sliding door section having top and side frame members, and a separate gusset member located in the angle formed by the top and side frame members at each upper corner of said door section and rigidly connecting the adjacent ends of said frame members, said gusset member having a door arm formed integral therewith and extending outwardly beyond the adjacent end of the top frame member.

55 Signed at St. Louis, Mo., this 30th day of April, 1928.

JULIUS A. SCHWEIG.
